ROTARY RETORT

Clarence B. Wisner, Orange, N. J., assignor, by
mesne assignments, to Coal Process Corpora-
tion, Dover, Del., a corporation of Delaware

Application April 17, 1929, Serial No. 355,913

35 Claims. (Cl. 202—218)

The invention relates to rotary cylinder retorts used for heat treating materials, and especially for the low temperature carbonization of coal by the processes set forth in my Letters Patent No. 1,490,357 of April 24, 1924, and in my pending application filed August 7, 1926, Serial No. 127,942, matured in Letters Patent No. 1,756,896, of April 29, 1930, for Coal ball manufacture, of which latter application the present application 10 is a continuation of certain common subject matter.

The object of the present improvement is to increase the capacity of the retort. In the indirect heating of fuels in a revolving container 15 all of the heat absorbed by the fuel must necessarily pass through the steel plate wall of the container. In the low temperature carbonization of solid fuels giving off their volatile hydrocarbons at critical temperatures, the best results 20 are obtained by heating the coal to a maximum temperature, not exceeding 975° F. which releases all, or practically all of the tar vapors, reduces the volatile in the coke product to less than 15 percent, and gives an ideal smokeless 25 fuel.

Great difficulty has been experienced in getting a commercial throughput because of the low temperature difference that must not be exceeded, because the steel in the rotary retort will 30 not stand a constant temperature much in excess of say 1100° F., and the fuel must be heated to at least 900° F. Under these conditions the coal, preheated to say 550° F. before it enters the carbonizing retort, must flow through the 35 plastic stage in a very thin stream, say at the rate of 5 pounds per square foot of wall surface of the fuel container.

That is to say, in a retort in which the diameter of the fuel container is 8 feet, the wall surface will approximate 25 square feet per foot of length, and a charge of 5 pounds per square foot will equal 125 pounds per foot of length. If the length is 125 feet, the maximum amount of coal that the container will hold at one time is 15,625 40 pounds, and if the carbonizing time is one hour, then the hourly capacity is less than 8 tons per hour.

I have discovered that if the above described thin stream is maintained until the fuel has 45 passed through the plastic or softened stage, which may last from 10 to 15 minutes, and the coal formed into balls with a coke structure, at the point where these balls begin to harden, the depth of bed may be increased from 5 pounds 50 per square foot of wall surface up to 10 to 15

pounds per square foot for the remainder of the time required to reduce the volatile in the balls to the extent desired, say to 15 percent or less.

This increasing of the depth of coal bed in 60 the discharge end of the coal container will considerably increase the hourly throughput of fuel through the retort, but I have also carried on full sized operations in which the wall surface of the container at the intake end of the retort was 65 increased by inserting as a part of the fuel container quadrant tubes with narrow flues surrounding the quadrants.

In this way I have increased the wall surface of the container per foot of length from 25 square 70 feet per foot of length, to 50 square feet per foot of length, and by the use of sextant tubes in place of quadrants, the wall surface may be increased to 60 square feet per foot of length; which sector tubes may be inserted either for 75 the entire length of the fuel container, or they may be limited to that part of the container in which the fuel passes through the plastic stage.

By so proportioning the number and size of sector tubes that each one comprises a carbonizing 80 container substantially equal in wall surface and cross area to a cylindric retort having a diameter of four feet, it is evident that each one of the sector tubes will give approximately one square foot of heating wall surface per cubic foot 85 of retort volume, which has been found to be the best unit ratio of volume to surface in a rotary retort.

And by forming the surrounding flues with a uniformly narrow width of from two to two and 90 one-half inches, for each 60 feet of length, or a corresponding width for greater lengths, the maximum transfer of heat through the walls of the tubes is obtained from a minimum volume of heating gases, by flowing the same through the 95 narrow flues at a high velocity of say 50 feet per second and upwards.

The invention also involves ancillary improvements in detail features of the construction and gas-tight swivel joints which may be embodied 100 in the retort for insuring the practical and proper operation of the same, all as illustrated in the accompanying drawings forming part hereof, in which—

30 Similar numerals refer to similar parts throughout the drawings.

In the illustration of the invention shown in Figs. 1 to 3 of the drawings, the main cylindric shell 20 of the retort may have a diameter of some 8 feet and a length of some 60 feet, and may be made of $\frac{5}{8}$ inch plate steel, completely covered on the outside by asbestos 20a or the like, to retain heat within the retort.

40 A plurality of sector tubes 21, preferably made of $\frac{1}{2}$ inch plate steel, are mounted within the cylindric shell parallel to the axis thereof, and as four sector tubes are shown, they will sometimes be referred to specifically as quadrant tubes; but it will be understood that a larger number of sector tubes may be used.

45 As best seen in Fig. 4, the quadrant tubes 21 are suitably proportioned and spaced inward from the cylindric shell to form an annular flue 22 about $2\frac{3}{8}$ inches wide, completely surrounding the arcuate walls 21a of the quadrant tubes, and extending the entire length of the cylindric shell; and they are likewise spaced apart to form the radial flues 23 about 2 inches wide, extending the entire length of the quadrant tubes, and all 55 communicating inwardly with each other (as below described) and outwardly with the annular flue throughout its length.

50 The central angle of the quadrant tubes may be slightly truncated to form comparatively narrow tangent walls 21c and within the square space formed by the tangent walls of the radiant tubes, is preferably located a central or axial core tube 24, which may be round in section and 16 or more inches in diameter, so as to form four somewhat 55 triangular flues 25 between the walls of the core tube and the tangent walls of the quadrant tubes; which triangular flues communicate with each other at a width of about 2 inches and with the corresponding radial flues of a similar width, so that the radial flues thus communicate inwardly with each other throughout the length of the quadrant tubes.

70 The proper spacing of the quadrant tubes within the cylindric shell and with respect to each other, may be accomplished by the use of

series of comparatively short angle flange clips 26, secured as by welding to the walls of the quadrant tubes, and to enable the quadrant tubes to be readily entered endwise into the cylindric shell, a series of bolts 26a, instead of the angle flanges, may be provided in one radial wall and in two of the tangent walls of adjacent quadrant tubes, which bolts may be retracted by unscrewing, to give freedom of movement until the tubes are all placed within the cylindric shell, after which they may be screwed to abut the opposing wall for securely and permanently locking the quadrant tubes in proper position within the cylindric shell around the core tube, as shown in Fig. 4.

80 The angle clips and locking bolts hold the tubes firmly against the retort wall, but allow for any unequal expansion arising from variations in the temperature between the quadrant tubes and the surrounding cylindric shell; it being understood that the bearing of the spacing flanges and locking bolts on the quadrant tubes against the wall of the cylindric shell is such as will permit a longitudinal movement of the one within the other, while if necessary, a sufficient 95 number of these bearings at one end or the other or at an intermediate point may be secured by angle clips on the retort wall to prevent a rotary movement of the quadrant tubes within the cylindric shell and to cause them to rotate together as a unit.

90 As best seen in Fig. 5, the square opening between the tangent inner walls at each end of the quadrant tubes is completely closed by substantially square steel plates 27, the edges of which 100 are preferably welded to the end edge portions of the quadrant tubes, and these plates completely close the ends of the core tube 24 and the ends of the triangular flues around the same, the ends of which core tube preferably abut and are welded to the inner faces of the square plate 27.

105 Likewise, the spaces between the radial wall 21b of the quadrant tubes at each end thereof, are completely closed by the radial plates or bars 28, which may be entered and welded between the 110 end edge portions of the radial walls of adjacent quadrant tubes; and the ends 28a and 28b of these bars are suitably flared in width to completely fill the space between the ends of the radial walls of the quadrant tubes, outward to 120 the circumferential line of the arcuate walls thereof; thus completely closing the ends of the radial flues formed between the quadrant tubes.

125 Truncated cone-shaped extensions 29 and 30 are secured to the intake end and the discharge 130 end, respectively, of the quadrant tubes, as by means of rim flanges 29a and 30a telescoping upon and completely around the ends of the arcuate walls of the tubes, as well as the outer ends of the radial bars 28, to which walls and bars the 135 rim flanges are preferably permanently secured as by welding.

140 The conical extensions 29 and 30 as common headers form intake and discharge chambers respectively communicating freely with the ends of the quadrant tubes without, however, communicating with any of the flues between or round the same; so that a charge of fuel or the like can flow freely from the conical intake chamber to the conical discharge chamber and will be 145 equally distributed to the quadrant tubes, when the retort is rotated upon its axis, which is slightly inclined from the horizontal in the manner to be described.

150 As shown in Figs. 1 and 2, the cylindric shell is

provided with a plurality of track rings 31 suitably spaced along its length for properly supporting the retort; which track rings ride upon suitable rollers 32, so positioned as to give the 5 axis of the retort a sufficient inclination from the horizontal from the fuel intake to the fuel discharge end, to cause the charge to flow or move from the one end to the other of the quadrant tubes, by a rotation of the retort upon its 10 axis, which rotation may be accomplished by a rack ring 33, driven by a pinion 34 to which suitable power may be applied; and thrust bearing rolls 32a may be provided for one or more of the track rings.

15 A stationary hood or housing 35 is located around the intake end of the retort, and may include a cylindric portion 35a somewhat larger in diameter than the cylindric shell, one end overlapping and surrounding the end of the shell and 20 being provided with an intervening, gas-tight, swivel joint 36, and also a truncated cone shaped portion 35b on the other end surrounding the end portion of the conical extension 29 on the intake ends of the quadrant tubes 21; so as to form an 25 enlarged heating gas chamber 37 around the same, communicating with the end of the circular flue 22 and also with the end portions of the radial flues 23, the ends of the quadrant tubes being extended a substantial distance beyond the 30 end of the cylindric shell for that purpose.

As well shown in Figs. 3 and 6, a rim ring 38 may be secured to the open end of the conical extension 29 of the quadrant tubes as by a flange 38a surrounding and welded to the free end 35 thereof. A short tubular intake neck 39 forming a restricted intake opening may be secured by a flange 39a to the rim ring 38, and is provided with a face flange 39b against which the rim of a stationary intake head 40 provided 40 with fuel feed pipe 40a, preferably provided with a valve, not shown, may abut for closing the intake end of the retort; which stationary head may be supported for a yielding rim pressure against the face flange of the neck in the manner 45 set forth but not to be claimed in my copending application filed January 13, 1925, Serial No. 2,146, and described more fully hereinbelow, with respect to which closure, the present application is a continuation of that application.

50 The truncated end of the conical extension 35b of the stationary head 35 surrounds a cylindric bearing flange 41 on the flange 39a of the intake neck 39; and a gas-tight swivel joint 42 is provided between the truncated end of the hood and 55 the bearing flange for completing the closure of the gas chamber 37 surrounding the intake end extension of the quadrant tubes.

As shown in Fig. 3, a rotary hood 43 is located around the discharge end of the retort, and may 60 include a cylindric portion 43a somewhat larger in diameter than the cylindric shell, and having one end permanently secured to the end thereof as by means of annular angle flanges 44 and 44a, and also a truncated cone-shaped portion 43b on the other end surrounding the end portion of the conical extension 30 on the discharge 65 ends of the quadrant tubes 21; so as to form an enlarged heating gas chamber 45 around the same communicating with the end of the circular flue 22 and also with the end portions of the radial flues 23, the ends of the quadrant tubes being extended a substantial distance beyond the 70 end of the cylindric shell for that purpose.

75 A discharge tube 30b extends from the truncated end of the conical extension 30 on the dis-

charge end of the quadrant tubes, into the side of a stationary discharge drum 46, which is provided with a gas-tight swivel joint 47 around the end of the discharge tube 30b and with a valved discharge spout 46a for the coal balls or other processed materials flowing through the quadrant tubes and carried from the conical extensions 30 into and through the discharge tube 30b as by means of suitably curved conveyer flanges 30c and 30d provided therein.

80 A stationary receiving drum 48 for heating gases is located around the discharge tube 30b, one side of which drum is provided with a gas-tight swivel joint 49 around the discharge tube 30b, and the other side of which drum is provided with a gas-tight swivel joint 50 around the cylindric neck with the small free end 43c of the conical extension of the rotary hood 43.

85 The receiving drum 48 communicates with a tubular conduit 51 leading from a source of supply of heating gases, and provided with suitable means, as a centrifugal blower not shown, for impelling the gases into the receiving chamber 45, through the flues of the retort, and to the enlarged chamber 37, the flues of the retort, the 100 enlarged chamber 37, and the outlet conduit 52 leading therefrom.

90 The gas-tight swivel joints 36, 42, 47, 49 and 50 between exterior and interior cylindric members, are all substantially alike, excepting as to 105 diameter, and minor details, and in all cases one of the swivel bearing members is suspended or sustained by inclined supporting links so as to press yieldingly by its own weight against the other swivel bearing member, and accommodate 110 itself to the endwise movements and the weaving of the rotary retort, in the manner set forth for the inlet end closing head in said pending application, Serial No. 2,146.

95 As shown in Figs. 6 and 7, the intake end head 115 40 is supported from below by links 53, the upper ends of which form bearings for trunnions 40b extending laterally on opposite sides of the head, preferably in the horizontal diameter thereof. The lower ends of these links are provided with 120 adjustable balls 53' seated in bearings 53" for permitting limited oscillation and turning, and the links are inclined upward toward the retort, so that the weight of the head acts to press the heads against the end of the retort; and at the 125 same time the head is free to move inward and outward and to swing upon its trunnion bearings, and also upon the ball bearings of the supporting links, so as to accommodate itself to the endwise and weaving movement of the end of 130 the retort. The frictional pressure of the intake head may be cushioned by the resistance of coil compression springs as 40c bearing against the abutment ring of the swivel joint 42 at the end of the stationary housing 35. If desired, the stationary heads may be suspended from above by 135 cables with adjustable links, in the manner described below for the abutment ring of the swivel joints.

140 A description of one of the swivel joints will suffice for all of them, and as shown in Fig. 9, each joint may include an annular flange 54 secured as by rivets 54' around the end of one of the stationary members of the retort, an annular flange 55 secured as by welding around the adjacent end of a rotary member of the retort, an intermediate abutment ring 56, having a cylindric sleeve 57 secured thereto as by rivets 57' telescoping into the adjacent end of the stationary member, and a flexible band 58 outside the 145 150

sleeve extending between and secured to, as by wrapping cables 58a around the abutment ring and the annular flange on the stationary member.

The annular flange 55 is preferably provided with a cylindric extension 55a, having its free end machined to form a smooth bearing 55a' for the machined end 56a of the abutment ring; and the abutment ring is preferably suspended by adjustable links, as 53a shown in Fig. 7, so in-

10 clined that the weight of the abutment ring 56 presses its bearing end 56a yieldingly against the bearing face 55a' on the annular flange 55, for effecting a closure of the joint. For convenience of assembly, the annular ring 55 and the abut-
15 ment ring 56 are preferably made in sections with ears 59, 59a and 59b on their ends, by which they may be secured together as by bolts 59c; and the gravity pressure of the abutment may be sup-
20 plemented by the weighted pulley 56b at the bot-
25 tom of the joint.

The end 54a of the stationary member is free to move endwise a limited extent around the cylindric sleeve 57, which telescopes therein to compensate for longitudinal expansion and contrac-
25 tion arising from variations in the temperature, and the closure of the joint is completed by the flexible band 58, which may be made of asbestos cloth or other heat resisting material, and is provided with enough fullness to accommodate the
30 relative movements of the parts to which it is connected.

The gas tight swivel joints 47 and 49 between the rotary discharge tube 30b and the stationary coal ball discharge drum 46 and the gas receiving drum 48, respectively, are similarly formed by a ring 55c secured to the discharge tube at a spaced interval from its end and having its opposite ends faced, operating against faced flanged thimbles 56c telescoped around the discharge tube and into the stationary drums 46 and 48, respectively, and being connected therewith by flexible bands 58c forming ring bellows surrounding and closing the joint; the flanged thimbles being spaced from the respective drums and being supported by inclined links, as 53 or 53a, so as to press yieldingly against the abutting faced ends of the ring 55, to accommodate endwise movement of the discharge tube.

In the operation of the retort, arranged as illustrated in Figs. 1 to 3 and the cylindric shell with the quadrant tubes therein being in rotation upon its axis, coal or other fuel to be thermodized or carbonized is received into the conical intake chamber 29 through the feed pipe 40a from a suitable source of supply, and flows thence into the several quadrant tubes as they are rotated successively into their lower positions, whence the coal flows through the quadrant tubes at a rate determined by the inclination and rate of rotation of the retort to the discharge end thereof and into the conical discharge chamber 30, whence it is conveyed as by lifters 30c and the spiral flange 30d into and through the discharge neck 30b, from which it is delivered into the stationary discharge drum 46 and the discharge spout 46a.

During the flow of coal through the retort as described, it is heated for thermodizing or carbonizing as the case may be, by heating fluids or gases received under an impelling pressure through the tubular conduit 51 into the stationary receiving drum 48 surrounding the fuel discharge neck 30b; whence the heating gases flow through the gas receiving chamber 45 surrounding the
75 fuel discharge end of the retort into and through

the circular, radial and triangular flues surrounding the several quadrant tubes, to the fuel intake end of the retort; whence it flows from the flues into the enlarged stationary hood chamber 37 surrounding the fuel intake end of the retort and escapes through the conduit 52 which may lead therefrom through a heating furnace, not shown, to the impeller for again circulating through the retort.

For a thermodizing process, it is preferred to maintain a temperature of from 450° to 600° F. in the fuel within the quadrant tubes, and for a low temperature carbonizing or a coal ball process, a temperature up to 975° F. in the fuel may be maintained in the quadrant tubes; and the temperature of the heating gases flowing through the flues should be such as to maintain the desired temperature within the quadrant tubes.

In the operation of retorts heated by the flow of gas or other fluid, it has been found that the maximum transfer of heat through the steel shell of the retort is best accomplished by the flow of heating gases through comparatively narrow flues in a stream about 2 or 2½ inches thick, at a high velocity of 50 feet per second and upwards, where the length of the retort is 60 feet or less. Thus the retort having a diameter of 8 feet, with 4 parallel quadrant tubes therein, spaced to form the communicating annular and radial flues, each having a width of from 2 or 2½ inches, gives a total flue orifice cross sectional area of some 1050 to 1350 square inches, which is a preferred flue orifice area for such a retort having an axial length of 60 feet or less. In retorts of greater diameters and longer lengths, the flue orifice area will be increased in proportion.

The heat which may be absorbed by the fuel tumbling over the hot steel walls of the retort tubes, depends, principally, upon two well known laws of heat transfer, that is, temperature difference and velocity; and it is obvious that when an indirect heating gas flows through the flues, a distance will be reached where the absorption of heat by the fuel will cool the heating gas to a temperature at which no more heat will be transmitted from the gas to the fuel.

The length of the retort, or rather the distance the heating gas shall flow, may be limited to meet this condition, or the flues may be increased in width to meet the heat requirements of larger lengths, and when the fuel must not only be heated to a given temperature, but must also be held at such temperature until the process is completed, it may be necessary to divide the flues into two or more longitudinal sections, or to increase the orifice of the flues and to provide for an independent flow of heating gases through each section, either in the same direction or in opposite directions, as may be desired.

Such a modification of the apparatus is illustrated in Fig. 11 of the drawings, wherein the retort may be constructed substantially the same as already described, but with a length of 100 feet and upwards. In such a retort, the sector tubes may continue from end to end, or only part way; but the heating gas flues are divided by a cross partition 60 welded to both sectors and retort wall in the circular radial and triangular flues, located at a point intermediate the ends of the retort so as to form a separate series of flues in each end half of the retort.

An annular drum 61 is provided around the cylindric shell, having gas-tight swivel joints 61a therewith at a substantial distance from the plane of the cross partition 60; which drum is divided

into two annular chambers 62 by a ring partition 60 α extending between the cylindric shell and the peripheral wall of the drum in the plane of the cross partition 60.

6 An annular series of slots 63 is provided in the cylindric shell opening into each one of the annular chambers 62 so as to give a free communication between the same and the several flues in the corresponding end of the retort; and each 10 annular chamber is provided with a tubular outlet or inlet 62a or 62b, as the case may be, for communicating with suitable conduits for receiving or discharging heating gases for circulating one way or another through the flues in the respective 15 sections of the retort.

By these means, heating gases may circulate in the same direction, either with or countercurrent to the flow of fuel therein, or the heating gases 20 may be circulated in different directions, either both from the annular drum each way to the ends of the retort, or vice versa, as may be desired for the particular process for which the retort may be used.

In all cases, the cross area of the heating gas 25 chambers at the ends of the retort, and the annular chambers at the middle thereof, as well as the total cross area of each series of slots 63, is equal to or slightly larger than the total cross area of all the flues between and around 30 the sector tubes, so that the heating gases will flow into and along the radial and triangular flues as well as the annular flue, for uniformly heating all of the walls of the sector tubes. If 35 need be, suitable baffles may be provided in the flues to direct the flow of heating gases therethrough.

In the manufacture of coal balls, it has been 40 found that the fuel under treatment absorbs the heat more rapidly and in a greater amount during the plastic stage before the coal balls are formed, than after the balls are formed; and that the productive capacity of the rotary apparatus can be materially increased by facilitating the movement of the fuel so as to flow in a 45 thinner layer during the plastic stage until the balls are formed, and then retarding the coal to flow in a thicker layer after the balls are formed.

This has been done by providing a spiral flange 50 about eight inches wide and one and one-third turns with an interval of about twelve inches between the overlapping ends, as shown at 64 in Fig. 1, in each sector tube at about one-third of its length from the intake end, at the place 55 where the coal balls have been formed; which flange acts as a screw conveyer to urge the fuel forward and to prevent a backward pressure therefrom during the plastic stage and insures a free flow of the fuel in a thin layer during 60 the ball forming period of the process.

It is also preferred to provide an arcuate flange 65, extending inward from the peripheral wall of each sector tube, to form a baffle or barrier to retard the flow of formed balls, and cause 70 them to flow in a thicker layer through the last two-thirds of the length of the tubes, after the balls have been formed and passed beyond the screw conveyer flange. These peripheral baffles are preferably located about one foot within the 75 discharge end of the tubes, as shown in Fig. 3, and also serve to prevent the delivery of balls from the peripheral portions of the sector tubes.

In addition to the peripheral flange baffles, it is also preferred to provide flanges or baffles 66 75 about twelve inches in width, across the tangen-

tial walls of the sector tubes at the discharge ends thereof, with an interval of about two inches between the ends 66' of the flange baffles and the side walls of the tubes, so as to prevent a discharge of the larger balls from the tubes until they form a layer higher than the flange baffle, while permitting the smaller balls to pass through the interval between the ends of the baffles and the radial walls of the tubes. 80

By placing one or more screw conveyer flanges 85 in proper places in the lengths of the tubes and providing flanged barriers at the outlet end thereof, the flow of fuel through the tube and the thickness of the layer thereof can be controlled as may be desirable or necessary for the 90 particular purposes of the process which may be performed in the apparatus.

I claim:—

1. A cylindric shell retort having its axis inclined from the horizontal and mounted for rotation on its axis, and a plurality of tubes 95 therein approximately cross sectional sectors of the shell and longitudinally parallel to the axis thereof and uniformly spaced from the shell and from each of the adjacent tubes to form a flue annular in cross section between the tubes and the shell and flues radial in cross section between adjacent tubes, said radial flues communicating inwardly with each other and outwardly with the annular flue. 100

2. A cylindric shell retort having its axis inclined from the horizontal and mounted for rotation on its axis, and a plurality of sector tubes 105 therein parallel to the axis thereof and spaced from the shell and from each other to form an annular flue between the tubes and the shell and radial flues between adjacent tubes, said radial flues communicating inwardly with each other and outwardly with the annular flue and all the flues being from two to two and one-half inches in width for each sixty feet of axial length. 110

3. A cylindric shell retort having its axis inclined from the horizontal and mounted for rotation on its axis, and a plurality of sector tubes 120 therein parallel to the axis thereof and spaced from the shell and from each other to form an annular flue between the tubes and the shell and radial flues between adjacent tubes, said radial flues communicating inwardly with each other and outwardly with the annular flue, and means for impelling heating gases through 125 each other and with the annular flue, and means for impelling heating gases through the flues. 130

4. A cylindric shell retort having its axis inclined from the horizontal and mounted for rotation on its axis, and a plurality of sector tubes 135 therein parallel to the axis thereof and spaced from the shell and from each other to form an annular flue between the tubes and the shell and radial flues between adjacent tubes, said radial flues communicating inwardly with each other and outwardly with the annular flue and all the flues being from two to two and one-half inches in width for each sixty feet of axial length, and means for impelling heating gases through the 140 flues. 135

5. A cylindric shell retort having its axis inclined from the horizontal and mounted for rotation on its axis, and a plurality of sector tubes 145 therein parallel to the axis thereof and spaced from the shell and from each other to form an annular flue between the tubes and the shell and radial flues between adjacent tubes, said radial flues communicating inwardly with each other and outwardly with the annular flue, and conical 150

- intake and discharge extensions on opposite ends of the sector tubes.
6. A cylindric shell retort having its axis inclined from the horizontal and mounted for rotation on its axis, and a plurality of tubes therein approximately cross sectional sectors of the shell and longitudinally parallel to the axis thereof and uniformly spaced from the shell and from each of the adjacent tubes to form a flue annular 5 in cross section between the tubes and the shell and flues radial in cross section between adjacent tubes, said radial flues communicating inwardly with each other and outwardly with the annular flue, and means closing the radial flues at each 10 end of the tubes.
7. A cylindric shell retort having its axis inclined from the horizontal and mounted for rotation on its axis, and a plurality of sector tubes therein parallel to the axis thereof and spaced 15 from the shell and from each other to form an annular flue between the tubes and the shell and radial flues between adjacent tubes, said radial flues communicating inwardly with each other and outwardly with the annular flue, and conical 20 intake and discharge extensions on opposite ends of the sector tubes, and means closing the radial flues at each end of the tubes.
8. A cylindric shell retort having its axis inclined from the horizontal and mounted for rotation on its axis, and a plurality of sector tubes therein parallel to the axis thereof and spaced 25 from the shell and from each other to form an annular flue between the tubes and the shell and radial flues between adjacent tubes, said radial flues communicating inwardly with each other and outwardly with the annular flue, and conical 30 intake and discharge extensions on opposite ends of the sector tubes, means closing the radial flues at each end of the tubes, and a head supporting 35 each end of the retort forming a chamber communicating with the ends of the annular flue and therethrough with the radial flues.
9. A cylindric shell retort having its axis inclined from the horizontal and mounted for rotation 40 on its axis, and a steel tube container therein parallel to the axis thereof and having an inside wall area in square feet substantially equal to its internal volume in cubic feet.
10. A cylindric shell retort having its axis inclined from the horizontal and mounted for rotation 45 on its axis, and a steel tube container therein parallel to the axis thereof and having an inside wall area in square feet substantially equal to its internal volume in cubic feet, there being an annular flue between the shell and the container from two to two and one-half inches in width for 50 each sixty feet of axial length.
11. A cylindric shell retort having its axis inclined from the horizontal and mounted for rotation 55 on its axis, and a steel tube container therein parallel to the axis thereof and having an inside wall area in square feet substantially equal to its internal volume in cubic feet, there being an annular flue between the shell and the container, and means for impelling heating gases through 60 the flue.
12. A cylindric shell retort having its axis inclined from the horizontal and mounted for rotation 65 on its axis, a steel tube container therein parallel to the axis thereof and forming a flue between the container and the shell, a cross partition transversely of the retort in the flue intermediate the ends of the retort dividing the flue transversely into sections along the retort, and 70 means for impelling heating gases through each 75 of the flue sections from one end to the other thereof.
13. A cylindric shell retort having its axis inclined from the horizontal, said shell being mounted for rotation on its axis and having an annular bearing face on one end thereof, a non-rotary head for said end of the retort having a rim face abutting the annular bearing face, trunnions extending laterally on two opposite sides of the head, and inclined links with ball and socket bearings on the lower ends and having bearings supporting the trunnions on their upper ends for yieldingly pressing the head by gravity against the end of the retort. 80
14. A cylindric shell retort having its axis slightly inclined from the horizontal, said shell being mounted for rotation on its axis and having an annular bearing face on one end thereof, a non-rotary head for said end of the retort having a rim face abutting the annular bearing face, link means yieldingly pressing the head against the end of the retort, and spring means cushioning said pressure by resisting the same. 85
15. A tubular retort including a rotary cylindric member having its axis slightly inclined from the horizontal and a non-rotary member at one end thereof, said members being communicably connected by a swivelled joint including an annular bearing face on the one, an abutment ring bearing against said annular face, and means supporting the abutment ring yieldingly pressing it by gravity against the annular bearing face. 90
16. A tubular retort including a rotary cylindric member having its axis slightly inclined from the horizontal and a non-rotary member at one end thereof, said members being communicably connected by a swivelled joint including an annular bearing face on the one, an abutment ring bearing against said annular face with a yielding pressure and having a sleeve on its other end telescoping into the adjacent end of the other member, and a flexible band connecting the abutment ring and said adjacent end around the telescoping sleeve. 95
17. A cylindric shell retort having its axis inclined from the horizontal and mounted for rotation on its axis, a plurality of tubes contained therein, approximately cross sectional sectors of the shell and longitudinally parallel to the axis thereof, a common header uniting the sector tubes at each end and forming therewith a coal container, the sector tubes being uniformly spaced from the shell and from each of the adjacent tubes to form a flue annular in cross section between the tubes and the shell and heating flues radial 110 in cross section between the adjacent tubes. 105
18. A tubular retort including a cylindric shell having its axis inclined from the horizontal and mounted for rotation on its axis, a tubular coal container therein parallel to the axis thereof and extending beyond the ends of the surrounding shell, stationary cylindric housings of substantially the same diameter as the outer shell covering the end portions of the coal container, there being annular bearing faces on opposite 115 ends of the outer shell, abutting rings yieldingly pressing against said annular bearing faces, and means for supporting the abutting rings and yieldingly pressing them against said annular bearing faces. 120
19. A tubular retort including a cylindric shell having its axis inclined from the horizontal and mounted for rotation on its axis, a tubular coal container therein parallel to the axis thereof and extending beyond the ends of the surrounding shell, stationary cylindric housings of substantially the same diameter as the outer shell covering the end portions of the coal container, there being annular bearing faces on opposite 125 ends of the outer shell, abutting rings yieldingly pressing against said annular bearing faces, and means for supporting the abutting rings and yieldingly pressing them against said annular bearing faces. 130
20. A tubular retort including a cylindric shell having its axis inclined from the horizontal and mounted for rotation on its axis, a tubular coal container therein parallel to the axis thereof and extending beyond the ends of the surrounding shell, stationary cylindric housings of substantially the same diameter as the outer shell covering the end portions of the coal container, there being annular bearing faces on opposite 135 ends of the outer shell, abutting rings yieldingly pressing against said annular bearing faces, and means for supporting the abutting rings and yieldingly pressing them against said annular bearing faces. 140
21. A tubular retort including a cylindric shell having its axis inclined from the horizontal and mounted for rotation on its axis, a tubular coal container therein parallel to the axis thereof and extending beyond the ends of the surrounding shell, stationary cylindric housings of substantially the same diameter as the outer shell covering the end portions of the coal container, there being annular bearing faces on opposite 145 ends of the outer shell, abutting rings yieldingly pressing against said annular bearing faces, and means for supporting the abutting rings and yieldingly pressing them against said annular bearing faces. 145
22. A tubular retort including a cylindric shell having its axis inclined from the horizontal and mounted for rotation on its axis, a tubular coal container therein parallel to the axis thereof and extending beyond the ends of the surrounding shell, stationary cylindric housings of substantially the same diameter as the outer shell covering the end portions of the coal container, there being annular bearing faces on opposite 150 ends of the outer shell, abutting rings yieldingly pressing against said annular bearing faces, and means for supporting the abutting rings and yieldingly pressing them against said annular bearing faces. 150

- shell, stationary cylindric housings of substantially the same diameter as the outer shell covering the end portions of the coal container, there being annular bearing faces on opposite ends of the outer shell, abutting rings yieldingly pressing against said annular bearing faces, means for supporting the abutting rings and yieldingly pressing them against said annular bearing faces, the said abutting rings having sleeves telescoping the adjacent ends of the stationary housings, and a flexible band connecting the abutting rings and said adjacent ends around the telescoping sleeves. 5 80
20. A tubular retort including a cylindric shell having its axis inclined from the horizontal, said shell being mounted for rotation on its axis, and having a housing at each end thereof, a plurality of sector tubes contained therein parallel to the axis thereof and extending beyond the ends of the surrounding shell into the housings, and a common header uniting the sector tubes at each end and forming therewith a coal container, the sector tubes being spaced from the outer shell and from each other to form an annular flue between the tubes and the shell and radial heating flues between the tubes, the flues having a combined orifice cross-sectional area of from 1050 to 1350 square inches for each sixty feet in axial length of an eight foot diameter retort, with the same relative proportions in other lengths and diameters. 10 35 30 35 40 45 50 55 60 65 70 75 85 90 95 100 105 110 115 120 125 130 135 140 145 150
21. A tubular retort including a cylindric shell having its axis inclined from the horizontal, said shell being mounted for rotation on its axis and having a housing at each end thereof, a plurality of sector tubes contained therein parallel to the axis thereof, and extending beyond the ends of the surrounding shell into the housings, a common header including the sector tubes at each end and forming therewith a coal container, the sector tubes being spaced from the outer shell and from each other to form an annular flue between the tubes and the shell and radial heating flues between the tubes, and means for impelling heating gases through the flues at a velocity of at least fifty feet per second. 10 35 40 45 50 55 60 65 70 75 85 90 95 100 105 110 115 120 125 130 135 140 145 150
22. A tubular retort including a cylindric shell having its axis inclined from the horizontal, said shell being mounted for rotation on its axis and having a housing at each end thereof, a plurality of sector tubes contained therein parallel to the axis thereof and extending beyond the ends of the surrounding shell into the housings, there being radial flues between the tubes, and a common header uniting the sector tubes at each end closing the radial flues and providing means for receiving coal into and discharging the residue from the sector tubes. 10 35 40 45 50 55 60 65 70 75 85 90 95 100 105 110 115 120 125 130 135 140 145 150
23. A tubular retort including a cylindric shell having its axis inclined from the horizontal, said shell being mounted for rotation on its axis and having a housing at each end thereof, a plurality of sector tubes contained therein parallel to the axis thereof and extending beyond the ends of the surrounding shell into the housings, there being radial flues between the tubes, and a common header uniting the sector tubes at each end closing the radial flues and providing means for receiving coal into and discharging the residue from the sector tubes, the sector tubes having an interior wall area in square feet substantially equal to the contained volume of the outer shell in cubic feet. 10 35 40 45 50 55 60 65 70 75 85 90 95 100 105 110 115 120 125 130 135 140 145 150
24. A tubular retort including a cylindric shell having its axis inclined from the horizontal, said shell being mounted for rotation on its axis and having a housing at each end thereof, a steel tube container therein parallel to the axis thereof and extending beyond the ends of the surrounding shell into the housings, a header at each end of said container providing means for receiving coal into and discharging the residue therefrom, there being space between the tube and housings forming an annular flue, and means for impelling heating gases through the flue at a velocity greater than fifty feet per second. 10 35 80 85 90 95 100
25. A tubular retort including a cylindric shell having its axis inclined from the horizontal, said shell being mounted for rotation on its axis and having housings on each end thereof, a coal container therein parallel to the axis thereof and extending beyond the ends of the surrounding shell into the housings, there being annular bearings on the opposite ends of the coal container, non-rotating heads covering said ends and having rimmed faces abutting the annular bearing faces, trunnions on opposite sides of the heads, and inclined links with bearings on their ends supporting the trunnions and yieldingly pressing the heads against the bearing faces. 100
26. A tubular retort mounted for rotation on its axis inclined from the horizontal, including a cylindric outer shell and a plurality of sector tubes forming an elongated fuel container therein parallel to the axis thereof, the tubes being spaced from each other and from the surrounding shell and forming radial flues between the tubes and an annular flue between the tubes and the shell, a central tube spaced from said tubes and forming an inner annular flue between the sector tubes and the central tube, the said annular flues communicating with each other through said radial tubes, the said fuel container extending beyond the ends of the outer shell and having restricted end openings, cylindric end housings of substantially the same diameter as the outer shell covering the extending portions of the fuel container and the ends with restricted end openings, said end housings and outer shell forming the outer wall of said annular flue, the said end housings being independently mounted on foundations parallel to the axis of the fuel container. 110
27. A tubular retort mounted for rotation on its axis inclined from the horizontal, including a cylindric outer shell and a fuel container therein extending beyond the ends of the outer shell, stationary end housings covering the extending end portions of the container, an expansion joint between the rotary and the stationary members, comprising an abutment ring having one end faced and communicably connecting the said rotary and stationary members and being supported by adjustable cables, a faced flange on the rotary member abutting the faced end of the abutment ring, the opposite end of the abutment ring telescoping the stationary member, and a flexible asbestos cloth ring bellows attached to the telescoping members near the adjacent ends thereof and surrounding and closing the telescoping joint. 120
28. A tubular retort mounted for rotation on its axis inclind from the horizontal, including a cylindric outer shell and a plurality of sector tubes therein forming an elongated fuel container, said sector tubes communicating with each other at their ends, a restricted intake opening on one end of the fuel container, an annular bearing surface around the intake opening, an annular head with a fixed rim flange abutting the said annular bearing surface, trunnions on 130

opposite sides of the head, and independent means supporting the trunnions having bearings at right angles to the container axis.

29. A tubular retort mounted for rotation on its axis inclined from the horizontal, including a cylindric outer shell and a plurality of sector tubes therein united at their ends into and forming an elongated unitary fuel container parallel to the axis thereof with a discharge tube on one end of restricted diameter, in combination with an annular discharge drum independently mounted at right angles to the axis of the fuel container with an annular opening facing the discharge tube and fitting loosely over it, a faced ring spaced from the end of the discharge tube and attached to it facing the drum, a faced flanged thimble telescoping the discharge tube and abutting said flanged ring and supported by adjustable cables, a flexible asbestos cloth ring bellows attached to said thimble and having its other end attached to the drum, the drum being spaced away from the ring to accommodate endwise movement of the discharge tube in the stationary drum.
30. A tubular retort mounted for rotation on its axis inclined from the horizontal, including a cylindric outer shell and a plurality of sector tubes therein united at their ends into an elongated unitary fuel container, each sector tube having one square foot of interior wall surface for each cubic foot of space within said sector tube forming said container, there being surrounding flues and passages, the combined orifice of which at right angles to the container axis approximates sixty square inches for each square foot of sector tube orifice parallel to the flue orifice.
31. A retort for carbonizing fuel and forming balls thereof, including a tubular container provided with intake means at one end and discharge means at the other end and having its

axis inclined from the horizontal and mounted for rotation on its axis for tumbling and advancing the fuel from the intake to the discharge end thereof, a spiral flange in the tubular container intermediate the ends thereof, for facilitating the movement of the fuel in a thin stream during the plastic stage and an arcuate flange in the discharge end of the tubular container for retarding the movement of the fuel in a thicker stream subsequent to the plastic stage of the carbonizing and ball forming process.

32. A retort including a steel tubular container mounted for rotation on an axis inclined from the horizontal and having an inside wall area in square feet substantially equal to its internal volume in cubic feet, walls forming a flue surrounding the tubular container, said flue having a width from two to two and one-half inches for each sixty feet of axial length, and means for impelling heating gases through the flue.

33. A retort including a steel tubular container mounted for rotation on an axis inclined from the horizontal and having an inside wall area in square feet substantially equal to its internal volume in cubic feet, and walls forming a flue surrounding the tubular container, said flue having a width from two to two and one-half inches for each sixty feet of axial length.

34. A retort including a steel tubular container mounted for rotation on an axis inclined from the horizontal, and walls forming a flue surrounding the tubular container said flue having a width from two to two and one-half inches for each sixty feet of axial length.

35. A retort including a steel tubular container mounted for rotation on an axis inclined from the horizontal and having an inside wall area in square feet substantially equal to its internal volume in cubic feet.
